CLARENCE M. HENDERSON AND EDGAR COCKS, OF BERKELEY, CALIFORNIA.

WALL-BED FOOT-RAIL CONNECTION.

1,228,915.

Specification of Letters Patent.

Patented June 5, 1917.

Application filed November 17, 1915. Serial No. 61,916.

To all whom it may concern:

Be it known that we, CLARENCE M. HENDERSON and EDGAR COCKS, citizens of the United States, residing at Berkeley, in the county of Alameda and State of California, have invented new and useful Improvements in Wall-Bed Foot-Rail Connections, of which the following is a specification.

Our invention relates to an improved construction for the foot rail and outer end leg supports for wall beds and the like.

It consists in the employment of socket pieces adapted to stand vertically when the bed is in its horizontal position and guided leg members slidable in the sockets, so that when the bed is in a horizontal position these leg members are held in proper supporting position. When the bed is turned up these leg members will slide out from the sockets and will then turn to right angles as the bed is brought into its vertical position.

The invention also comprises details of construction which will be more fully explained by reference to the accompanying drawings, in which—

Figure 1 is a side elevation of the bed extended in full lines and turned up in dotted lines.

Fig. 2 is a perspective view of the corner socket.

Fig. 3 is a perspective view of the pivot plug.

Fig. 4 is a vertical section on line 4—4 of Fig. 5, showing the plug and socket.

Fig. 5 is a detail elevation of one corner of the foot showing the same parts.

Fig. 6 is a cross section on line 6—6 of Fig. 5, partly broken away.

Fig. 7 is a detail section on line 7—7 of Fig. 6.

The object of our invention is to provide a convenient and substantially automatically operating leg frame, which is adapted to support the foot of the bed, when extended, and which is foldable to lie parallel with the bed frame when the latter is turned up into its vertical position; the movements of the leg frame being substantially automatic and needing no special attention.

As shown in the drawings, A represents the side rails of a bed, pivoted at 2 and capable of being turned up into a vertical position, as shown in dotted lines, in which position the leg supports 9^b hang parallel with the side rails of the bed. When ex-

tended, these legs hang in a vertical position, resting upon the floor and supporting the outer end of the bed.

The construction of this portion of the bed, in detail, is as follows: 4 and 4^a are the two semicircular halves of a socket-piece which are designed to fit together and be secured by a bolt 5 passing through the upper part. The segment 4 is here shown as 65 being cast with the bracket 6 to which the bed rail A is secured. The segment 4^a has formed with it a socket for the extension rail 7 which unites this leg with the corresponding leg at the other side of the foot 70 of the bed.

8 represents the upward extension of the foot of the bed, and 9 is an elongated plug which is slidable in the socket piece 4—4^a. This plug has grooves 10 formed upon opposite sides and the socket piece has corresponding projections or lugs, as at 11, upon which the grooves 10 are slidable to extend or shorten the legs. The lower end of the plug 9 is here shown as enlarged, as at 9^a, 80 and 9^b is a tubular foot-piece which forms the continuation of the plug and has a foot adapted to rest upon the floor when the bed is extended.

The operation of this portion of the bed 85 will be as follows: When the bed stands in its vertical position out of use the legs 9^b will hang parallel with the side rail A. In this position the grooves 10 in the plug 9 will slide upon the pins 11 of the socket 4 until the pins are located in the upper closed ends of the grooves. The upper end of this plug is made hemispherical and its curvature is concentric with the curvature of the upper ends of the grooves 10, so that the foot portion having dropped down until the pins 11, at each side are in the head of the plug 9, the latter and the legs will turn so as to fall into the position shown in Fig. 1; the sockets 4 being grooved or channeled, as 90 at 12, to allow the legs to take this position.

When the bed is opened out and the rails A are moved into horizontal position, the legs will turn upon the pivot pins 11 and the plug will have moved out of the groove in the socket piece so as to stand in proper alignment to rest upon the floor when the bed is fully extended. When this occurs the grooves 10 of the plug 9 will move upon the pins 11, allowing the plug to slide up into the socket piece until a sufficient portion of it is contained in the socket to steady the 105 110

legs and prevent them from being pushed to one side or the other, the socket piece serving as a guide for the legs.

The lower portion 9^b of the legs is tubular, as previously described, and fitting over the enlarged lower end 9^a is secured thereto by means of indentations 13, on opposite sides of the plug, and a punch is used to correspondingly indent the tubular portion 10 9^b into said indentations 13, as at 13^a, thus locking them firmly thereto.

By this construction we provide legs for the outer or foot end of the bed which will be automatically turnable into position to support said foot portion, and being slideable into the socket, the upper part will be guided and stiffened by the socket so as to prevent any undesirable movement of the bed when in position. When the bed is 20 raised this leg member will slide outward until the upper ends of the plug are in position to turn about the pivots in the socket portion and they will thus turn so that the foot will hang parallel with the side rails 25 when the bed is in its upturned position.

Having thus described our invention, what

we claim and desire to secure by Letters Patent is—

In a foot support for a bed comprising two-part corner sockets each part being provided on its inner face with a pin and formed on its outer face with an integral bracket to which an end of the adjacent bed rail is secured, a bolt securing the parts of the socket together above the pins, a plug in each socket provided with grooves to receive slidably the pins, the upper end of each plug being rounded concentric with the upper ends of the grooves, the lower ends of the grooves being closed by a shoulder adapted to abut the lower end of the respective socket, and a foot extension carried by the shoulder of each plug.

In testimony whereof we have hereunto set our hands in the presence of two subscribing witnesses.

CLARENCE M. HENDERSON.
EDGAR COCKS.
